UNITED STATES PATENT OFFICE.

EDWARD K. WARREN, OF THREEOAKS, MICHIGAN, ASSIGNOR TO THE
WARREN FEATHERBONE COMPANY, OF THREEOAKS, MICHIGAN.

STIFFENING CORD OR TAPE.

SPECIFICATION forming part of Letters Patent No. 739,460, dated September 22, 1903.

Application filed December 3, 1900. Serial No. 38,440. (No model.)

To all whom it may concern:

Be it known that I, EDWARD K. WARREN, a citizen of the United States, residing at the village of Threeoaks, in the county of Berrien, 5 and State of Michigan, have invented certain new and useful Improvements in Stiffening Cords or Tapes, of which the following is a specification.

This invention relates to stiffening cords or 10 tapes, and is an improved construction of stiffening cords or tapes in which quill substance is utilized.

The objects of this invention are primarily an improvement in the stiffening-strand itself, 15 although when the strands are assembled they form a blade of great rigidity and strength, owing to the arrangement of the parts, it being very desirable to form these stiffeners into blades, as they are made up of short lengths, 20 which require break-joints to secure the best results. This improved structure, while it utilizes quills of all sizes, is especially adapted for the utilization of medium-sized quills, as that will entirely avoid dividing the quills into 25 parts, it being necessary merely to split them down one side and remove the pith. Where the quills are large, they can be split or divided into longitudinal strips for the purpose.

The objects of the particular arrangement 30 and of the details of construction will fully appear in view of these statements in the detailed description to follow.

I accomplish the objects of my invention by the devices and means described in this 35 specification.

The invention is fully defined and pointed out in the claims.

A structure fully embodying the features of my invention is fully illustrated in the 40 accompanying drawings, forming a part of this specification, in which—

Figure 1 is an illustration of the improved strand in process of manufacture, no apparatus or machinery being illustrated in connection. Fig. 2 is a detail view of a portion 45 of a completed strand. Fig. 3 is a detail view of a stiffening-blade made up of such strands. Fig. 4 is a detail transverse sectional view through the blade appearing in Fig. 3. Fig. 50 5 is a transverse enlarged detail sectional view through one of the strands, the wrapping-

thread being omitted. Fig. 6 is a transverse enlarged detail sectional view through one of the strands, the wrapping-threads being omitted, made of a narrow section of quill, the 55 edges not being overlapped, as in Fig. 5.

In the drawings similar letters of reference refer to similar parts throughout the several views.

The quills are first stripped of their plumage. The quill substance is then split open and the pith-like substance removed by sand-paper, emery-wheels, scraping, or other suitable means. The quill, if a large one, is split into strips of appropriate width, as appears 60 at A of Fig. 1, and where the quills are larger they can be split into halves in the first instance, which is my usual process of treating such quills. When strips of the shell portion of the quill have been prepared and cut to 65 the proper width, one end of the same will be found to be thinner than the other. They are then arranged in series, the thick end of one part lapping onto the thin portion of the other, after the manner indicated in Fig. 1, 70 such strips of quill being indicated by the letter A. This material is then wrapped longitudinally around a central strand or thread B, forming a scroll or roll, as in Fig. 5 or 6. A wrapping-thread C is then wound around 75 the same to retain the quills securely in this position. The quills are preferably steamed or otherwise moistened during this process, so that they will be easily conformed, and I prefer to dip the tips of the same into cement, so 80 that the different sections will be securely cemented together. The strand when completed is clearly illustrated in Fig. 2. I desire to remark that when the quill substance 85 is softened and heated and covered by cement it can be brought to the form of the strand and be retained there without the aid of a thread. It requires, however, considerable care in the manufacture, and I prefer to use the thread around each strand separately 90 on account of the greater security. Several of these strands can be placed side by side and securely wound together by wrapping-threads E E, as clearly appears in Fig. 3, and where more than two strands are wound together a row of stitches F should extend 95 down through the center, which will hold the 100

wrapping-threads in position exactly according to the method appearing in United States Letters Patent No. 389,993, issued to me on the 25th day of September, 1888. The strands thus assembled can be utilized as a stiffener without any further treatment. I, however, prefer to treat the blade so formed in the manner described in United States Letters Patent No. 559,827, issued to myself and Mr. 5 Jonas H. Holden on the 12th day of May, 1896, whereby the wrapping-threads will be closely incorporated with the quill substance and the whole made into a smooth even stiffening-blade of great rigidity and strength. I also 10 desire to state that the strands D or the strands without the wrapping-threads can be incorporated into blades by a braiding-machine, as clearly appears in United States Letters Patent No. 611,298, issued to me on 15 the 27th day of September, 1898. The strands can also be used in woven fabrics. Single strands can of course be used where a small cord is desired.

I desire to remark that this structure can 20 be considerably varied without departing from my invention. While the strand B is of very great advantage during the assembling of the parts and gives great longitudinal strength to the finished strands, I am 25 aware that by exercising care and caution the same can be omitted. The advantages of its presence, however, will be wanting, and I prefer to utilize it. Other variations have 30 already been indicated, and I think still further modifications will suggest themselves to 35 those skilled in the art to which this invention pertains.

Having thus described my invention, what I claim as new, and desire to secure by Letters 40 Patent, is—

1. In a stiffening material, a strand comprising a central thread inclosed by overlapping, longitudinally slotted and rolled sections of quill portions of feathers, the parts

being suitably cemented together; and a 45 wrapping-thread embracing the same, for the purpose specified.

2. In a stiffening material, a strand comprising a central thread inclosed by overlapping longitudinally slotted and rolled sections 50 of the quill portions of feathers; and a wrapping-thread embracing the same, for the purpose specified.

3. In a stiffening material, a strand comprising strips of quill portions of feathers 55 rolled longitudinally upon themselves and into a roll; and a wrapping-thread embracing the same, for the purpose specified.

4. In a stiffening material, a strand comprising strips of quill portions of feathers 60 rolled longitudinally upon themselves and into a roll, for the purpose specified.

5. A strand made up of the quill portions of feathers which are rolled into longitudinal rolls with overlapping meeting ends and suitable means of retaining the same in position.

6. A strand made up of the quill portions of feathers which are rolled into longitudinal rolls with suitable means of retaining the same in position.

7. A stiffening-blade made up of a series of strands consisting of the quill portion of feathers, which is rolled longitudinally into a roll and compacted together and retained in a flat braid by wrapping threads around the 70 same, as specified.

8. A stiffening-blade made up of a series of strands consisting of the quill portion of feathers, which is rolled longitudinally into a roll and compacted together and retained in a flat braid, as specified.

In witness whereof I have hereunto set my hand and seal in the presence of two witnesses.

EDWARD K. WARREN. [L. S.]
